DESIGN FOR A FLASK

Darrell E. Briner, Winchester, Ind., assignor to
Hazel-Atlas Glass Company, Wheeling, W. Va.,
a corporation of West Virginia

Application April 23, 1934, Serial No. 51,493

Term of patent 14 years

To all whom it may concern:

Be it known that I, DARRELL E. BRINER, a citizen of the United States, residing at Winchester, in the county of Randolph and State of Indiana, have invented a new, original, and ornamental Design for Flasks, of which the following is a specification, reference being had to the accompanying drawing forming part thereof.

Figure 1 is a perspective view of a flask showing my new design,

Figure 2 is a similar view taken at a different angle, and

Figure 3 is a horizontal sectional view thereof.

I claim:

The ornamental design for a flask, as shown.

DARRELL E. BRINER.
